PAPER HOLDER FOR PENCILS

Edmond A. Lar Rieu, Jr., Oakland, Calif.

Application August 6, 1935, Serial No. 34,925

3 Claims. (Cl. 242—55.5)

This invention relates to improvements in writing instruments such as mechanical pencils or fountain pens.

It is an object of the invention to provide, 5 within the pen or pencil, an instantly available supply of writing paper.

Another object of the invention is to provide improved means for permitting removal of desired amounts of the paper from the pen or 10 pencil.

A further object of the invention is to provide means for readily re-loading the pencil or pen with fresh quantities of paper after the previous quantity thereof has been exhausted.

15 The invention possesses other objects and features of advantage, some of which, together with the foregoing, will be set forth in the detailed description of the invention which follows. It is to be understood however that the invention is not to be limited to the specific embodiments 20 thereof shown and described as various other forms thereof may be employed within the scope of the appended claims.

Referring to the drawing:

25 Figure 1 is a side elevational view of a mechanical pencil embodying the improvements of my invention.

Figure 2 is a front elevational view of the device shown in Figure 1.

30 Figure 3 is an enlarged cross sectional view of the pencil. The plane in which this view is taken is indicated by the line 3—3 of Figure 1.

Figure 4 is a side elevational view of a pencil incorporating a modified form of the invention.

35 In detail, I provide the usual pencil or fountain pen body 5, having threaded into one end thereof the tip 6 containing the mechanism 7 for propelling the lead 8, and having threaded into the opposite end thereof a plug 9 which carries the eraser 10, with a slot 11 extending axially of the body 5 and opening at the end thereof adjacent the plug 9.

40 Pivotedly mounted on a screw 12, tapped into the body 5, is a metallic bar 13 the main portion of which is offset from the periphery of the body, as is shown in Figure 1, to provide a slot 14. The upper end 15 of the bar is bent to lie against the periphery of the plug and is provided with a notch 16, opening at one edge thereof, 45 which engages a headed screw 17 tapped into the plug 9. The pocket clip 18 may be conveniently mounted on the bar 13, by means of rivets 19, or otherwise.

45 The construction just described permits the 55 bar 13 to be swung outwardly about the pivot

screw 12 to the position indicated by the dotted lines in Figure 2, thereby allowing the plug 9 to be rotated to remove it from the end of the body 5 which latter operation opens the upper end of the body and permits a coiled roll 20 of 5 paper strip to be pushed axially into the bore of the body with the outer end of the strip projecting through the slot 11. The plug 9 may then be replaced and the bar 13 swung to again engage the notch 16, at the end thereof, with 10 the screw 17. This again establishes the slot 14 through which the end of the paper strip is drawn. Referring to Figure 2 it will be seen that by pulling on the end of the paper strip, as much 15 thereof as desired may be withdrawn from the roll 20 and, by using the edge of the bar 13 as a knife, the desired quantity of the paper may be torn from the main strip.

20 It is of course obvious that the slot 11 may be made as long as desired so as to accommodate 25 paper of greater width and one method of doing this is shown in Figure 4. In this modification the slot 21 extends for a considerable distance axially along the body 5 and is provided along one edge thereof with a metal tearing strip 22 which is affixed to the body by tabs 23 which are bent arcuately to seat in peripheral grooves 24 formed at spaced intervals along the body. The 30 pocket clip 25, in this modification, may be attached, in the usual manner, directly to the pen 35 or pencil. If desired, the edge of the tearing strip 22 adjacent the slot may be serrated to facilitate easy tearing of the paper.

The most valuable feature of the invention is that, should a person be required to take or give 35 notations or memoranda, a convenient supply of writing paper is always at hand; the only operation necessary to procure it being to withdraw it from the pencil or pen and tear it off.

Another valuable feature is that the operation 40 of reloading the pencil with a fresh roll of paper is simplified to a maximum degree, and entails no more labor than inserting additional lead in the pencil, merely removing the plug 9, slipping a new 45 roll of paper into place within the body 5 and replacing the plug and securing the end of the bar 13, being all that is necessary.

I claim:

1. A paper holder comprising a tubular body, 50 into which may be inserted a coiled strip of material, having a slot through the wall thereof opening at one end of said body and through which an end of said coiled strip of material may be drawn, a plug screwed into the end of said body and having a portion thereof closing said slot at 55

its open end, and a bar secured at one end to said body and at the other end to said plug and spaced from said body to provide a passage between said bar and the periphery of said body through which 5 the end of said strip of material drawn through said slot may be passed.

2. A paper holder comprising a tubular body, into which may be inserted a coiled strip of material, having a slot through the wall thereof 10 opening at one end of said body and through which an end of said coiled strip of material may be drawn, a plug screwed into the end of said body and having a portion thereof closing said slot at its open end, and a bar pivotally mounted 15 at one end thereof on said body and having means at the other end thereof for removably engaging said plug, said bar being spaced from said body to provide a passage between said bar and the periphery of said body through which the end of

said strip of material drawn through said slot may be passed.

3. A paper holder comprising a tubular body, into which may be inserted a coiled strip of material, having a slot through the wall thereof 5 opening at one end of said body and through which an end of said coiled strip of material may be drawn, a plug screwed into the end of said body and having a portion thereof closing said slot at its open end, a headed screw disposed in 10 said plug, and a bar pivotally mounted at one end thereof on said body and provided at the other end thereof with a notch for engaging the screw in said plug, said bar being spaced from said body to provide a passage between said bar and the 15 periphery of said body through which the end of said strip of material drawn through said slot may be passed.
